UNITED STATES PATENT OFFICE

103,835

DESIGN FOR A CURTAIN DISPLAY RACK

Trowbridge H. Stanley, Bronson, Mich., assignor to L. A. Darling Company, Bronson, Mich., a corporation of Delaware

Application December 18, 1936, Serial No. 66,618

Term of patent 7 years

To all whom it may concern:

Be it known that I, Trowbridge H. Stanley, a citizen of the United States and resident of Bronson, county of Branch, State of Michigan, have invented a new, original, and ornamental Design for a Curtain Display Rack, of which the following is a specification, reference being had to the accompanying drawing, forming a part thereof.

In the drawing, the figure is a perspective elevation of a curtain display rack, showing my new design.

I claim:

The ornamental design for a curtain display rack, substantially as shown.

TROWBRIDGE H. STANLEY.
